H. F. Keil Inventor
By his Attorney J. O. Fowler

UNITED STATES PATENT OFFICE.

HENRY FRANCIS KEIL, OF NEW YORK, N. Y., ASSIGNOR TO LIBRARY BUREAU, OF ILION, NEW YORK.

DRAWER-PULL.

1,210,945.

Specification of Letters Patent.

Patented Jan. 2, 1917.

Application filed April 24, 1916. Serial No. 93,317.

To all whom it may concern:

Be it known that I, HENRY FRANCIS KEIL, a citizen of the United States of America, and a resident of New York, in the county 5 and State of New York, have invented a certain new and useful Drawer-Pull, of which the following is a specification, the same being a full, clear, and exact description of the invention, such as will enable 10 others skilled in the art to which it appertains to make and use the same.

The invention relates to devices commonly designated as drawer-pulls which are attached to a receptacle contained in a cabinet, 15 etc., in such a manner that access to it is had by drawing or sliding it out horizontally in its guides or frame by means of said manually actuated device.

The invention also comprises means for 20 holding cards, and is particularly adapted for use in connection with card index cabinets, as it is adapted to serve not only as means for opening the drawer, but also to retain the cards in position by means of a 25 rod extending inwardly from the drawer-pull proper upon which the cards may be mounted, the outer end of the rod terminating in a knob which may be securely fastened to the front portion of the drawer.

To attain the desired end the invention 30 consists in the construction and arrangement of parts hereinafter particularly described and shown in the drawings attached hereto and forming a part of this specification, 35 illustrative of one embodiment of the invention, and in which—

Figure 1 is a partial sectional view of a 40 drawer of a cabinet equipped with my improved pull; Fig. 2 is an elevation of the rod therefor before being operated upon; Fig. 3 is an elevation of the latter with notches punched in the side portions thereof; Fig. 4 is a view in section of the head or knob of the pull having duplex concentric 45 bores made therein; Fig. 5 is a view partly in section showing the two opposite side portions of the inner bore upset to engage the notches in the rod; Fig. 6 is a sectional view of an exteriorly threaded sleeve made with 50 an angular head; and Fig. 7 is a view partly in section of the assembled device showing the threaded sleeve mounted on the rod, and the rim of the outer bore of the knob upset so as to engage the said angular head of the 55 sleeve.

Like numerals of reference indicate like parts in all the views.

Referring particularly to the drawings 1 denotes a drawer having a bore at the front and rear portions thereof respectively constructed and arranged to contain the inner end of a rod 3 and an internally threaded bushing 2.

In order to adapt the rod 3 to serve for the purpose desired, I take a cylindrical rod 65 of the desired size, as illustrated in Fig. 3, and form, preferably by punching, at least one and preferably two opposite side portions thereof adjacent to the front end of the same, flaring notches 4, as shown in 70 Fig. 3. The knob 5 is preferably made with two concentric bores or recesses 6 and 8 of different diameters, the inner one 8 being preferably smaller than the outer one 6. The knob is preferably constructed so that 75 there shall be two burs 9 and 7 respectively located at the outer extremities of said burs. The rod 3 is now held so as to register with the smaller recess of the knob and the front end of the same is inserted into the said 80 bore 8 of the knob 5, which latter is then upset at least one and preferably two side portions thereof at the bur 9 so as to lie against and within the said notches, thereby 85 permanently and securely attaching together the knob 5 and rod 3.

A stepped sleeve 10 formed with an exterior thread on the rear end thereof and having an enlarged angular and preferably hexagonal head 11 is now slid onto the rod 90 3, and the angular head 11 inserted in the groove 6, after which the bur 7 is upset at at least one part thereof and preferably around the entire circumference of the same so as to lie against and inclose the rear end 95 of the head 11, in order to securely and permanently fasten the rod 3, sleeve 10 and knob 5 together in a rigid relation. The rod 3 thus has an enlarged medial portion the rear end of which is threaded, and has at 100 least one notch 4 formed in the same at its front end and beyond the front portion of the head 11 of the said enlarged portion comprising the sleeve 10.

In operation the threaded sleeve 10 is engaged with the bushing 2 of a drawer. When employed in connection with a card cabinet, the rod 3 having cards mounted thereon is inserted in the drawer 1, and the threaded sleeve 10 screwed into the bushing 110

2 of the drawer. In instances where my invention is desired to be used merely and solely as a drawer-pull, the rod 3 need not extend inwardly beyond the end of the 6 threaded sleeve.

I wish it to be understood that I do not desire to be limited to the particular use of the exact details of construction shown and described, for various modifications will occur to a person skilled in the art.

What I claim as my invention is:-

1. In a device of the class described, a rod having an enlarged medial stepped portion, the outer end of which latter is threaded, 15 the rod also having at least one notch formed in the same at its inner end beyond the inner portion of the head of the said enlarged portion, in combination with a knob having two concentric bores or recesses 20 of different diameters respectively constructed and arranged to contain the notched end of the rod and the enlarged medial portion thereof, the metal around the open ends of said recesses being upset to lie respectively

against the said notch and the enlarged 25 head.

2. In a device of the class described, a rod having a stepped sleeve mounted on the medial portion thereof, the outer end of which sleeve is threaded, the said rod having at 30 its end at the inner side of the head of the sleeve at least one notch formed in the same, in combination with a knob having two concentric communicating bores or recesses of 35 different diameters respectively constructed and arranged to contain the notched end of the rod and the enlarged medial portion thereof, the metal around the open ends of said recesses being upset to lie respectively 40 against the said notch and the enlarged head.

In testimony of the foregoing specification I do hereby sign the same in the city of New York, county and State of New York this 18th day of April, 1916.

HENRY FRANCIS KEIL.
